F. DUTCHER.
RAILWAY SIGNAL TORPEDO.
APPLICATION FILED OCT. 8, 1915.

1,194,973.

Patented Aug. 15, 1916.

UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,194,973.

Specification of Letters Patent. Patented Aug. 15, 1916.

Application filed October 8, 1915. Serial No. 54,873.

To all whom it may concern:

Be it known that I, FRANK DUTCHER, a citizen of the United States, residing at Versailles, in the county of Allegheny and State 5 of Pennsylvania, have invented certain new and useful Improvements in Railway Signal-Torpedoes, of which the following is a specification, reference being had therein to the accompanying drawing.

10 This invention relates to improvements in railway signal torpedoes and more especially to that type which is circular in shape and composed of one or more separate parts between which an explosive tablet or 15 pound is placed.

Referring to the accompanying drawings, Figure 1 is a perspective view of a torpedo involving my present improvement. Fig. 2 is an inverted perspective view of Fig. 1. 20 Fig. 3 is a sectional view taken on the line 3-3 of Fig. 1, showing a slight modification. Fig. 4 is a perspective view showing the parts of the torpedo in separated relation.

25 The general form of torpedo here shown is well known and it comprises a top portion 1 which has an outwardly bulged part 2, and an annular flap or flange 3. An explosive tablet 5 is made of a shape to fit within the 30 cavity 4 formed by the bulged portion 2, and a disk 6 is placed over the explosive tablet and made of a size corresponding to the size of the top portion and including the flange 3 thereof. The cavity 4 has a layer of water- 35 proof cement 7 placed therein before the tablet is placed in position, and then a waterproof cement coating 8 is placed on the outer flat side of the tablet and the disk 6 then placed in position. No cement is 40 placed between the flap and annular flange 3 of the top 2 and the disk 6, which is the case with paper or fibrous torpedoes of this type heretofore constructed so far as I am aware.

45 The rail-engaging strap 9 is attached to the torpedo by means of a second disk 10 which has strap receiving openings 11. This disk 10 is of a size corresponding to the size of the disk 6 and is placed outside 50 thereof as shown. The annular flange 3 of the top or cover portion 2 and the edges of

the disks 6 and 10 are united by suitable stitches 12. The completed torpedo is then subjected to a very thin coating of shellac or other suitable waterproofing compound 55 which will fill the openings or interstices formed by the stitching, and a waterproof torpedo is provided.

As shown in Figs. 2 and 3 the rail-engaging strap passes through the openings 11 and between the disk 10 and the disk 6. Cement is placed under the rail-engaging strap thus filling the openings 11 which lie under the strap, and this cement serves to bulge the strap upward as shown at 13, Figs. 60 2 and 4, thus preventing the strap from moving endwise on the torpedo and locking it in place against accidental removal. However, the bulges in the strap 9 and the cement sufficient to cause the bulges may be 65 omitted as shown in Fig. 3.

One of the objects of this improvement is to unite the flanges of the separated parts of the torpedo without the use of cement or metal. When cement is located between the 75 flanges of the parts of the torpedo at a point or points outside of the explosive, a hard annular flange results, and when the torpedo is exploded this hard annular flange will sometimes segregate and fly in particles that would inflict injury to a person standing by. In the construction here shown, the annular flange is composed solely of paper and fibrous stitching, and therefore of such a nature that when it flies, it 80 85 will not inflict injury to any one who might be standing near.

A further object of my present improvement is to connect the rail-engaging strap to the torpedo without the use of any metal 90 whatever, and in a simple, cheap and efficient manner.

Having thus fully described my invention what I claim and desire to secure by Letters Patent is:

1. An improved railway torpedo comprising a two-part case, an explosive within the case, the case having a laterally extending annular flange, and a disk applied to the case, the two-part case and disk united by 95 sewing only, the disk having openings to receive a rail-engaging strap, and a rail-en- 100

gaging strap passing through the said openings.

2. An improved railway torpedo comprising a two-part case having an annular flange, an explosive within the case, a disk applied to the bottom of the case, the flange of the two-part case and the disk united by sewing only, the disk having openings located between the sewing and the center of

the disk, and a rail-engaging strap passing through the openings of the disk. 10

In testimony whereof I hereunto affix my signature in the presence of two witnesses.

FRANK DUTCHER.

Witnesses:

R. W. JUNKER,
A. MACDONALD.
